UNITED STATES PATENT OFFICE

GREGORY BROWN, OF BRIDGEPORT, CONNECTICUT, ASSIGNOR TO BRIDGEPORT BRASS COMPANY, OF BRIDGEPORT, CONNECTICUT

CLUSTER STEM

Application filed June 27, 1928. Serial No. 288,713.

This invention relates primarily to electrical fixtures, and more especially to an improved cluster stem used as a part of certain forms of electrical lighting fixtures.

- 5 Cluster stems or the like are generally used to connect fixtures of the pendant type with the ceiling or wall supports therefor, and to provide concealing means for the conductor wires leading to the light sockets thereon.
- 10 In the past, many of these cluster stems have been made of two or more parts among which was a cast or sheetmetal part, having an opening therein for the passage of the electrical conductor wire. The edges of this opening
- 15 are, in many instances, rough and would abrade the covering of the wire and either damage the insulation or the covering, destroying the usefulness and appearance thereof. Other parts which were generally
- 20 provided, were expensive to manufacture and to assemble, being made in many instances, of solid stock in which threads and shoulders were formed by machining the same and necessitating pins or other fastening means to
- 25 assemble them to other parts of the cluster stem.

One of the objects of this invention is to provide an improved electrical fixture of the pendant type.

- 30 Another object of this invention is to provide a fixture support engaging means, which will be economical to manufacture, light in weight, sturdy and of pleasing appearance.

- 35 Another object of this invention is to provide an improved cluster stem or the like, for use with electrical fixtures.

- 40 A further object of this invention is to generally improve the structure of cluster stems or the like, to increase the usefulness and efficiency thereof.

- 45 A still further object of this invention is to provide in a structure having a tubular body part, and an eye part, novel means to rigidly connect these parts together.

- 50 To these and other ends, the invention consists in the novel features and combinations of parts to be hereinafter described and claimed.

In the accompanying drawings:

- 55 Fig. 1 is an illustration of an electrical

fixture, embodying the features of this invention;

Fig. 2 is a view of a cluster stem, embodying the features of this invention;

Fig. 3 is a section on line 3—3 of Fig. 2; 55

Fig. 4 is a section of the tubular part of the cluster stem, taken on line 4—4 of Fig. 3;

Fig. 5 is a section on line 5—5 of Fig. 4, and

Fig. 6 is a section on line 6—6 of Fig. 4. 60

Fig. 1 illustrates one form of an electrical

fixture of a pendant type, wherein the fea-

tures of this invention are embodied. In

this figure, the numeral 10 indicates the ceili-

65 g or wall from which the fixture is sus-

pended. A device commonly known as a

hickey 11, is connected to the electrical out-

let box disposed within the ceiling or wall 10.

The hickey 11 is provided with the usual

threaded stud 12. The electrical circuit 70

wires 13 of the fixture are connected to power

wires contained in the outlet box.

A cluster stem 14 adapted at one end to

be screwed upon the stud 12, extends in this

instance, downwardly therefrom. The cir-

75 circuit wires 13 are threaded through an open-

ing 15, provided in the side of the stem 14,

passing downwardly therethrough and out

at the lower end thereof, and are connected

to the light socket 16. In their passage to 80

the light socket 16, the wires 13 may be

threaded in and out of chain links 17, form-

ing part of the fixture illustrated. A ceiling

or wall cap 18 is generally provided and is

retained in position to cover the upper end 85

of the stem 14, as well as the opening in the

wall, by means of a clamp screw 19, which is

threaded through a part of the cap 18 and

engages the stem 14.

The cluster stem 14 comprises a tubular 90

body part 20, preferably formed of thin sheet

metal being, in this instance, a short length

of drawn tubing, and an eye part 21, formed

of comparatively heavy metal wire. The

95 tubular body part 20 at one end thereof, is

provided, during its manufacture, with a

thickened wall portion 22. The exterior of

the portion 22 is provided with corrugations

or the like 23, to provide finger gripping

means as well as for ornamental purposes. 100

The interior of the portion 22 is provided with screw threads 24 for use in attaching the stem to the stud 12, or other fixture supporting means.

5 The eye part 21 is provided with a ring like base portion 25 integral with the eye proper, which base portion is preferably but not necessarily formed by bending the respective end of a wire blank (the intermediate portion of which is shaped to form the eye) in a plane perpendicular to the plane of the eye and inwardly so that they form opposite sides of a transverse ring element.

10 The base portion 25 is disposed transverse to the axis of the eye part 21. The outer diameter of the portion 25 is of such dimension that it will enter the lower end of the body part 20, and be disposed therein transversely to the longitudinal axis thereof and concentric therewith. When so disposed within the part 20, the portion 25 acts as a conductor bushing for this end of the stem, which due to the curved surfaces at its upper and lower face, protects the conductor wire passed therethrough against damage to its insulating covering by abrasion.

15 The part 20 of the stem 14 is provided with an internal shoulder 26, formed, in this instance, by spinning the material thereof inwardly, forming a groove 31 upon the exterior of the stem for decorative purposes. The shoulder 26 is disposed in position to engage the base portion 25, and limit the amount of its insertion into the end of part 20. After the portion 25 has been inserted into the part 20, the remaining end portion or end edge of part 20 is spun or turned inwardly and upwardly about the base portion 25, whereby the same is securely pressed and clamped against the shoulder 26, and retained against removal from the part 20.

20 The tubular body or shell and the ring shaped base of the eye member have integral interlocking means for positively holding the ring against angular movement in the shell, the metal of the shell in the ring-seating portion thereof being displaced by bending to present inwardly directed locking projections that engage parts of the inserted conductor-receiving member so that the device may be screwed into and out of place by manipulation of the outwardly extending loop portion of the eye member. In this manner the eye and the shell are very effectively and permanently interconnected. In the particular example illustrated, portions 27 and 28 that depend from the base portion 25, to connect the eye part 21 thereto, are securely engaged at either side thereof by portions 29 and 30 of the end portion or rim of the mouth of the part 20. The portions 29 and 30 act against the depending portions 27 and 28 of the eye part to prevent it and its base portion 25 from twisting or turning relatively to the part 20.

25 The above described structure and the novel manner of constructing the same, provides an especially sturdy cluster stem or the like, which is economical to manufacture, light in weight, and sturdy and attractive in appearance. There are no separate parts, such as, a threaded bushing for engaging the support, requiring expensive tools to manufacture, and pins or other means to assemble it to the tube, or an eye part which is threaded upon the end and may become loosened during use, nor any parts which are likely to abrade the conductor wire and damage its insulation and the appearance of its covering.

30 While I have shown and described a preferred embodiment of my invention, it is understood that it is not to be limited to all of the details shown, but is capable of modification and variation which will lie within the spirit of the invention and the scope of the appended claims.

35 What I claim is:

1. A cluster stem comprising a drawn tubular shell having a portion of its side wall near the lower end thereof spun to present an inwardly directed shoulder, a conductor receiving element comprising a transverse ring-shaped base portion set in the mouth of said shell against said shoulder and having an integral depending longitudinal loop or eye, the wall of said shell at the rim or mouth portion thereof and below said shoulder being bent inwardly to hold said ring-shaped part against said shoulder, and integral means on the mouth portion of said shell and on said conductor receiving element respectively in locking engagement with each other to prevent said conductor receiving element from turning in said shell.

40 2. In a cluster stem, the combination of an elongated tubular shell having an inwardly directed shoulder adjacent the lower end thereof, an eye member comprising an eye part depending from a ring-like base portion, said base portion being formed by bending inwardly the ends of an element of which the intermediate portion constitutes said eye part, with said ends in a plane substantially perpendicular to said eye part and curved to form the ring, and means for securing said base portion in the mouth of said shell against said shoulder with said eye projecting exteriorly of the shell.

45 3. A cluster stem comprising a drawn tubular shell having a portion of its side wall near the lower end thereof bent to present a transverse shoulder, and a conductor-receiving element comprising a ring-shaped base portion set in the mouth of said shell against said shoulder and having a depending loop or eye outside of the shell, the wall of said shell at the rim or mouth portion thereof and below said shoulder being bent inwardly to hold said ring-shaped part against said shoulder and to lock said ring-

shaped part against rotation in said shell whereby said shell may be rotated by turning said loop or eye, said shell having a screw connection at its upper end for securing it to a fixed support.

5 4. A cluster stem comprising a tubular shell of thin sheet metal having an inwardly spun annular portion adjacent one end thereof of creating an inwardly directed shoulder interiorly of the shell, an element comprising a ring-shaped base portion set in the mouth of said shell against said shoulder and having an integral depending eye, the wall of said shell between said shoulder and the edge 10 of the shell being bent or folded to hold said ring-shaped base portion securely against said shoulder and to interlock said base portion and shell against relative rotation.

15 In witness whereof, I have hereunto set my hand this 25th day of June, 1928.
